CLAIM

The ornamental design for a hatch awning, as shown and described.

DESCRIPTION

FIG. 1 is a front elevation of the hatch awning showing my new design;

FIG. 2 is a side elevation thereof;

FIG. 3 is a rear elevation thereof;

FIG. 4 is a top plan view thereof;

FIG. 5 is a bottom plan view thereof; and

FIG. 6 is a front perspective view thereof with the broken lines shown for illustrative purposes only and forming no part of the claimed design.
